(57) **CLAIM**

The ornamental design for a card with an ornamental rectangle and IC chip, as shown and described.

DESCRIPTION

FIG. 1 is a perspective view of a card with an ornamental rectangle and integrated circuit (IC) chip showing my new design;

FIG. 2 is a front view of the card of FIG. 1;

FIG. 3 is a rear view of the card of FIG. 1;

FIG. 4 is a right side elevational view thereof;

FIG. 5 is a left side elevational view thereof;

FIG. 6 is a front elevational view thereof; and,

FIG. 7 is a rear elevational view thereof.

The numerals and indicia depicted by means of broken lines in the drawing are shown for illustrative purposes only and form no part of the claimed design.
